BOX FOR TABLETS OR THE LIKE

Minoru Meshino, Tennojicho, Abeno-ku, Osaka, Japan, assignor to Morishita Jintan Co., Ltd., Osaka, Japan

Filed Feb. 23, 1960, Ser. No. 59,486

Term of patent 14 years

(Cl. D58—11)

FIG. 1

FIG. 2

FIG. 3

FIG. 4

FIG. 5

FIG. 6.

Fig. 1 is a front elevation view of a box for tablets or the like, showing my new design;

Fig. 2 is a rear elevation view thereof;

Fig. 3 is a right side elevation view thereof;

Fig. 4 is a left side elevation view thereof;

Fig. 5 is a top plan view thereof; and

Fig. 6 is a bottom plan view thereof.

The dominant features of my design reside in the portions shown in full lines.

I claim:

The ornamental design for a box for tablets or the like, as shown and described.
